Specification of Letters Patent. Patented June 16, 1914.

Application filed October 17, 1906. Serial No. 339,399.

To all whom it may concern:

Be it known that I, CLARENCE I. ZIMMERMAN, a citizen of the United States, residing at Niagara Falls, County of Niagara, State of New York, have invented certain new and useful Improvements in Electric Converters, of which the following is a specification.

This invention relates to the conversion 10 of alternating current into uni-directional current or other forms having special qualities applicable to various electrotechnical uses.

I have hereinafter described several distinct types of apparatus suitable for carrying out my improved method, and although the separate types are distinguishable by various specific characteristics, nevertheless, they all embody the basic idea of my 20 invention.

My system includes one or more asymmetric conductors together with means for accumulating a very appreciable electrostatic charge. In those species wherein I 25 have used a mercury vapor tube as an asymmetric conductor, I have combined with it an electrostatic condenser of the ordinary type. In those species in which an electrolytic asymmetric conductor is used, I 30 make use of the peculiar electrostatic capacity of the asymmetric conductor itself, thus, in a sense, combining the condenser and asymmetric conductor in a single unit.

I am aware that mention has heretofore 35 been made of the electrostatic capacity of an electrolytic cell consisting of two aluminum plates immersed in a suitable electrolyte. I am also aware that electrolytic cells containing one aluminum electrode and one carbon or iron electrode have been used for the 40 rectification of current. I am not aware, however, that it has ever been proposed to utilize simultaneously the rectifying and electrostatic properties of such cells, particularly when disposed in such systems as 45 are hereinafter described.

According to my improved method of rectification, the alternating current may be converted into uni-directional current, either steady or pulsating, and this unidirectional current may have a voltage higher 50 than that of the original alternating cur-

rent. In fact, according to some of the species hereinafter described, the uni-directional voltage may be several times higher 55 than the original alternating current voltage. So far as I am aware, this result is broadly new.

As will appear from the following detailed description, the system of my present 60 invention is a rectifying system in which, instead of simple rectification, a condenser is so connected that it acts to boost the voltage at the load circuit, the entire system being such that by changing the connections 65 for the load circuit, the condenser may be used to equalize the load potential instead of boosting it.

In the drawings annexed to and forming 70 a part of this specification, Figure 1 is a diagrammatic representation of a simple form of rectifier using a mercury vapor asymmetric conductor and an electrostatic condenser of the usual type. Fig. 2 gives a similar 75 system utilizing two vapor tubes and a condenser. Fig. 3 illustrates a system similar to that of Fig. 1, except that the rectified current is of positive polarity at the central or intermediate terminal. Fig. 4 corresponds to Fig. 2 except that by a reversal of 80 the asymmetric conductors, the polarity of the rectified current is reversed. Fig. 5 is a diagrammatic representation of a system in which the electrostatic condenser and asymmetric conductor are combined in a single 85 electrolytic cell. The output of this system is comparable to that of the system shown in Fig. 1. Fig. 6 is an electrolytic rectifier yielding current of reverse polarity with respect to that delivered by the system of Fig. 90 5. Fig. 7 represents a system in which a "positive" rectifier is associated with a "negative" rectifier in such a way that the condensers charge in parallel and discharge 95 in series. In a sense, this is a consolidation of the systems shown in Figs. 1 and 3, the former illustrating what I choose to term a "negative rectifier" and the latter a "positive rectifier". Fig. 8 shows a system in 100 which three vapor lamps or valves are utilized in connection with two large electrostatic condensers to yield direct current of substantially constant voltage. Fig. 9 shows a system in which three electrolytic cells are

provided with aluminum plates disposed in such a way that the cells act both as asymmetric conductors and as condensers, and when acting as condensers are charged in parallel and discharged in series and yield a direct current voltage appreciably higher than that of the alternating current source. Fig. 10, shows an arrangement for increasing still further the difference between the potential of the direct current output and the alternating current input. This differs from the arrangement of Fig. 9 by the inclusion of a second electrolytic condenser connected between the direct current terminals. Fig. 11 shows a new type of asymmetric conductor, and illustrates its use in a system of rectification. Fig. 12 illustrates a polyphase system for producing and utilizing a rotating electrostatic charge. Figs. 13, 14, 15, 16 and 17 are curves illustrating electrical potentials between various parts of the systems shown in the other figures.

In several figures of the drawing I have illustrated a mercury vapor tube or lamp as an asymmetric conductor or valve to transmit current in one direction and to prevent the flow of current in the opposite direction. Such a tube or lamp may consist, as illustrated in Fig. 1, of an inclosing envelop 1 provided with an anode 2 of solid material, and a vaporizable cathode 3 of mercury. A second or auxiliary anode 4 is also provided and is supplied with current from a battery 5 or other source of energy, for the purpose of maintaining a continuous arc from the mercury cathode 3. This auxiliary arc, or side branch, serves to maintain the tube in such a condition that it will transmit current tending to flow from the solid anode 2 to the mercury cathode 3, but will prevent current flow in the opposite direction. The valve-like action of a mercury vapor tube is also present in an electrolytic cell of the type having an aluminum electrode, in combination with an electrode of inert material, such as carbon, platinum or iron, and an electrolyte capable of developing an insulating coating on or about the aluminum electrode. Such a cell will transmit current readily from the inert or carbon electrode to the aluminum electrode, but will not transmit any appreciable current in the opposite direction. Probably this asymmetric action is due to the formation of a coating of oxid, hydroxid or other material on the aluminum plate, this coating being of extreme thinness and high resistance. These properties of an aluminum electrolytic cell are well known.

In addition to the asymmetric property of an aluminum cell, I find that by proper disposition of the electrodes, a very appreciable electrostatic capacity may be obtained, and furthermore, that the condenser action of the cell may be utilized in connection

with the other elements here shown, for the rectification of alternating current, and for its conversion into unidirectional current of pulsating character or into current of substantially constant potential. According to my invention advantage is taken of the properties of an electrolytic cell, of combining in itself both the properties of an asymmetric conductor and the properties of a condenser, and this dual rôle which the electrolytic cell is able to play, I may take advantage of by substituting an electrolytic cell in place of a vapor tube and a tinfoil condenser in the system herein disclosed and claimed.

In the following detailed description of my invention, I have illustrated species utilizing vapor electric valves, and other species using electrolytic valves, and in those systems using vapor electric valves I have arranged tin foil or similar condensers in those parts of the circuits requiring electrostatic capacity, while in the systems utilizing electrolytic valves I have relied on the electrolytic cell itself to supply the necessary capacity. It should be understood that the illustrations of electrolytic cells shown in the drawings are merely diagrammatic, and that in practice I could increase the electrostatic capacity by increasing the area of the aluminum electrode in any suitable way.

Fig. 1 illustrates a system of rectification, and comprises, in addition to the vapor electric device heretofore described, an electrostatic condenser 6 of the tin foil or other well known type, and an alternating current source, such as a transformer having a primary 7 and a secondary 8. The cathode 3 of the vapor tube is connected to one of the leads 9 of the transformer secondary 10 and a condenser 6 is connected between the anode 2 of the vapor tube and the other lead 10 of the alternating current source. The condenser 6 is preferably large enough in capacity to permit an appreciable flow of current from the transformer main 10 through the vapor tube to the other terminal of the transformer. As current cannot flow back through the vapor tube to equalize the charge in condenser 6 when the potential of the source reverses, there results a negative charge on the conductor connecting the condenser to the vapor tube, this charge establishing a potential across the conductor terminals equal to the maximum potential across the transformer secondary 8 less the drop in the rectifying arc tube. That this value is correct will be readily apparent upon consideration of the flow of current out of the condenser when the transformer lead 10 becomes positive, and the absence of return current when that lead becomes negative. As lead 10 becomes positive, it communicates a positive charge to one side of condenser 6, and thereby induces

a negative charge in the other side; as a result, current is driven from anode 2 through the vapor tube to the other main.

As the voltage drop across the vapor tube 5 may be relatively small say 10 to 20 volts, and the voltage of the source may be as high as several thousand volts the condenser receives substantially the maximum potential of the transformer secondary and 10 takes up a charge corresponding to that potential. When the source reverses, the condenser is prevented from discharge by the valve-like action of the vapor tube, and tends to maintain across its terminals a constant potential equal to that of the maximum value developed by the alternating current source. After the first cycle of the alternating current source, the condenser connected as above described neither charges 15 nor discharges but maintains a definite steady voltage across its terminals. If, now, means are provided for taking off a small part of this charge, the energy so taken off will be substantially constant potential and at a voltage equal to the maximum pressure of the alternating current supply less the drop in the rectifier tube. For conveniently utilizing this charge, I have provided the transformer terminals 9 20 and 10 with terminals 11 and 12, and I have connected a third terminal 13 to the conductor connecting the condenser 6 to anode 2 of the vapor tube. Translating devices such as lamps, motors, etc., connected 25 between terminals 12 and 13 will receive uni-directional current of substantially constant voltage, the current passing through the translating devices from terminal 12 to terminal 13. It should, of course, be 30 understood that the capacity of condenser 6 must be made large enough to supply the desired energy to the translating devices without great loss in the potential of the charge, as otherwise, the translating devices 35 will receive pulsating current instead of constant potential current.

My system of rectification provides not only for the production of constant potential direct current as above described, but 40 also for the production of pulsating uni-directional current. This may be obtained by connecting the translating device between the terminals 11 and 13, the terminal 11 being positive and the terminal 13 being 45 negative. Between these terminals the potential periodically varies from zero to practically twice the voltage of the transformer secondary, for when terminal 11 is at its maximum negative value, terminal 13 is at 50 substantially the same potential, but when the polarity of the source reverses, the condenser and source act in series to develop substantially double potential across the terminals 11 and 13, and thus make this 55 double potential available to perform use-

ful work. In practice, it sometimes happens that this maximum potential falls a little below the calculated value because of irregularity in the wave shape of the transformer current and because of leakage in 70 the condenser and voltage drop in the vapor tube, factors which are well understood by persons skilled in the art, and which need not be referred to except as sources of the slight discrepancies which may arise between the theoretical values of the voltages 75 and the values obtained in practice. These differences are mainly of theoretical interest and will not be further discussed herein.

A somewhat homely explanation of the double potential available momentarily between terminal 11 and 13 may be made as follows: Assuming that the condenser 6 is receiving its charge, the potential at its terminals will rise to substantially that of the 80 transformer secondary 8 (neglecting the voltage drop in the tube) then if we were to cut the wires between the condenser and transformer before the potential had time to reverse, we would have stored in the condenser a charge, the voltage of which is 85 constant and equal to the maximum instantaneous voltage of the transformer secondary. Then let us assume that the transformer voltage reverses in polarity and after that reversal is complete, we connect the condenser with the secondary, in such a way that it serves to boost the voltage of the secondary. This will give a voltage 90 between the free terminal of the secondary, substantially double that originally impressed on the condenser, the effective current supply source being the condenser 6 95 acting in series with the transformer second 8 between points 11 and 13. But instead of 100 performing this connecting and disconnecting operation by hand as above assumed, the rectifier of the present system does it for us. At each half wave it connects the condenser 105 for a charge and at the subsequent half wave it disconnects the condenser at one end 110 leaving it connected in at the other end in such a way that it boosts the reversed voltage of the transformer secondary.

For a better understanding of the potential differences between various parts of the system described, reference may be had to Fig. 13 in which these differences are graphically illustrated. Let it be assumed 115 that the horizontal line 13' is a curve representing the potential at the terminal 13 in Fig. 1 and that vertical distances above this line are positive potentials with respect to terminal 13. For purposes of discussion, the terminal 13 may be considered as at 120 earth potential. When the condenser of Fig. 1 has been charged to its maximum voltage, the potential of terminal 12 will be positive 125 with respect to terminal 13 by an amount equal to the maximum momentary difference 130

of potential between 11 and 12 and may therefore be represented by the horizontal line 12' of Fig. 13, this being located above line 13 by a distance corresponding to the maximum instantaneous voltage of the alternating current source. As the terminals 11 and 12 are directly connected to the alternating current source the potential of 11 with respect to 12 may be properly illustrated by the sine curve 11' of Fig. 13.

The vertical distance between curves 12' and 13' represents the open circuit potential difference available across the terminals 12 and 13. Of these two terminals 12 is positive with respect to 13. Similarly the vertical distance between curves 11' and 13' at any particular point of time represents the instantaneous potential on open circuit between terminal 11 and terminal 13. Thus at the instant of time marked A-B, terminal 11 is at its maximum positive value with respect to terminal 12 and is at twice this value with respect to terminal 13. By following along the curve to the instant marked C-D, it will be seen that terminal 11 drops to the potential of terminal 13, so that in passing from A-B to C-D it drops to zero from a maximum equal to twice the maximum instantaneous difference of potential between 11 and 12, or in other words twice the maximum instantaneous voltage of the alternating current source.

It will be understood that when the load current is small with respect to the capacity of the condenser the curves of Fig. 13 will be substantially accurate for illustrating voltage available at the respective terminals for sending current through the load. If the load current is so heavy as to pull down on the condenser voltage at each discharge thereof, the wave shapes illustrated in Fig. 13 will be flattened out and modified somewhat, as will be readily understood.

Fig. 2 illustrates a transformer 14 and vapor tubes 15 and 16 connected respectively to the transformer terminals in such a way as to permit current to flow from either terminal to a binding post 17 which thereby becomes a positive terminal of the consumption circuit. A condenser 18 of relatively high electrostatic capacity is connected in shunt with vapor tube 16. The transformer secondary terminals are connected directly to binding posts 20 and 21, from which connections may be made to the positive terminal 17 through the loads 22 and 23. When the polarity of the transformer secondary is such as to send current from anode to cathode in the vapor tube 15, a positive charge is introduced on plates 24 and a similar inductive charge is induced on the opposing plates 25. A charge so imprisoned cannot escape through the vapor devices 15 and 16 because of their asymmetric action, and can only pass off by way

of terminal 17 and one of the load circuits 22 or 23. If the load is connected at 23, then the discharge passes from 17 to 21 and delivers energy at substantially the maximum voltage of the transformer secondary, 70 it being understood that the condenser is of ample capacity with respect to the resistances of the load circuit. If the load is connected at 22 instead of at 23 the charge of condenser 18 will pass from 75 terminal 17 to terminal 20 and will be at substantially double the voltage of the transformer secondary, because of the fact that under these conditions, the condenser voltage is added to that of the 80 transformer secondary or in other words the condenser boosts the transformer voltage. In addition to the energy transmitted from terminal 17 to terminal 20 by way of condenser 18, a certain amount is also 85 transmitted directly from the source by way of vapor tube 16, and this latter energy is, of course, at the potential of the transformer secondary.

Fig. 14 illustrates graphically the instantaneous differences of potential between the terminals 17, 20 and 21 when no current is being used in the load circuits 22 and 23. For convenience of reference, the terminal 21 has been considered at zero potential and therefore capable of representation by the horizontal line 21' shown in Fig. 14. With this as a datum line the instantaneous values of the terminal 17 are properly represented by a parallel straight line 17' separated from the line 21' by a distance corresponding to the maximum difference of potential of the alternating current source. Terminal 17 is always positive with respect to terminal 21 and consequently line 17' appears above line 21'. The potential difference between the terminal 21 and the terminal 20 is properly represented by a sine curve 20' symmetrically disposed with respect to the line 21'. 100

From an inspection of Fig. 14 it will be seen that under the condition of no load the terminal 17 is at a constant potential above the terminal 21 equal to the maximum impressed voltage of the alternating source, 115 and that it is at a potential above the terminal 20 by a potential which periodically varies from zero to substantially twice the impressed maximum voltage. This high voltage is of course produced by charging 120 the condenser 18 in parallel with the source and discharging it in series therewith. Although the curves shown in Fig. 14 properly illustrate the potential difference of the terminals under conditions of no load, they are 125 not, unless the large condenser 18 be considered of infinite capacity, strictly accurate for a loaded system. If the condenser is not large or if the demands on it are heavy, the stored energy may be exhausted 130

sufficiently to give a noticeable drop in the condenser voltage. This state of affairs is illustrated diagrammatically in Fig. 15, assuming that either or both of the loads 22 and 23 are connected in.

From an inspection of Fig. 15 it will be seen that the partial exhaustion of the condenser causes a slight droop in curve 17'. This means a decrease in the voltage on the load until curve 17' intersects the charging potential 20'. Then the voltage on the load and the voltage across the condenser go up together and the condenser starts off with a new charge.

If the system shown in Fig. 2 be over-loaded, the exhaustion of the condenser causes a rapid falling off in the potential of the terminal 17'; at complete exhaustion the curve 17' intersects the curve 21'. In other words, the terminals 17 and 21 reach the same potential. It happens, however, that the curve 17' will not cross the curve 21', for further demands of the load 22 are supplied by energy passing directly through vapor device 16 to the terminal 17. This vapor device therefore performs an important function in preventing the condenser 18 from charging up with the wrong polarity in case of an excessive demand in the load circuit 22.

Fig. 3 shows a system in many respects similar to that of Fig. 1, and differing principally in the fact that the asymmetric conductor 26 is reversed, or in other words, is connected to the transformer secondary by its anode-lead instead of by its cathode-lead. This makes the conductor 27 joining the condenser and vapor tube positive with respect to the transformer terminals 28, 29 but otherwise the voltage relations are substantially the same as that of the system shown in Fig. 1. For convenience in description, the system shown in Fig. 1 may be termed a negative rectifier, and the system of Fig. 3 may be termed a positive rectifier, and these terms are hereinafter used to describe elements of systems in which these positive and negative devices are combined to coöperate as for instance in Fig. 7.

Fig. 4 shows a system differing from that of Fig. 2 by a reversal of the asymmetric conductors to render the intermediate terminal negative instead of positive. To secure this result, the vapor tubes 30 and 31 have their anodes connected directly to the intermediate conductor or terminal 32, and their cathodes connected respectively to the transformer mains 33 and 34 and the corresponding load terminals 35 and 36. The condenser 38 is connected in shunt with one of the tubes in the same way that condenser 18 of Fig. 2 is in shunt with its tube 16.

Fig. 5 illustrates my invention as embodied in an electrolytic asymmetric conductor of the aluminum type. The system is

made up of a source of alternating current 39 connected directly to load terminals 40 and 41. Across these terminals is connected an electrolytic cell 42 comprising a small aluminum plate 43 and a large aluminum electrode 44, an electrolyte 45 of the character commonly used in aluminum asymmetric conductors, an inert electrode 46 of carbon, iron or platinum, connected to an intermediate load terminal 47. In practice, I make electrode 44 of large area and capable of holding a high electrostatic charge, and I make the smaller electrode 43 of such small size that it possesses little or no electrostatic capacity. I consider that the electrostatic capacity of an aluminum electrode is comparable to that of an ordinary tin foil condenser, and that the aluminum plate is one armature of the condenser, the electrolyte the other armature, and the insulating film or coating on the aluminum plate is the dielectric. For a complete understanding of my invention as embodied in apparatus of the type illustrated in Fig. 5, it should be noted that the electrolytic cell is a rectifier as well as a condenser. When the polarity of the source is such that terminal 41 is positive, a positive charge is communicated to the aluminum plate 44, as one armature of a condenser, and a corresponding negative charge is induced in the electrolyte 45, it being understood that this phenomenon is accompanied by a flow of current from the electrolyte and the small aluminum electrode 43. The latter opposes substantially no opposition to the flow of current from the electrolyte to the plate, although it does oppose a practically prohibitive resistance to a flow of current in the opposite direction. The electrolyte being once charged negatively remains in that condition until equilibrium is restored through some other path than that furnished by the aluminum electrode since current can never flow directly from the aluminum to the electrolyte. If, now, a circuit is completed between terminals 41 and 47 or between 40 and 47, so that energy can enter the cell by way of the inert electrode 46, then the condenser will tend to discharge and produce equilibrium between the electrolyte and the metal of plate 44. If the condenser is of sufficient capacity with respect to the return or load circuit between, say terminals 41 and 47, then the condenser will maintain a uni-directional current of substantially constant potential in this load circuit, and together with the rectifying action of the small aluminum electrode, will serve to convert the alternating current of the source into direct current for use between terminals 41 and 47. If the external circuit is completed by connecting the load between terminals 40 and 47, then the condenser acts in series with the source to boost the voltage to substantially twice that of the

source, excluding, of course, the CR., and leakage losses in the cell itself. The output is unidirectional and pulsating. The entire system of Fig. 5 is comparable to that of Fig. 1, and since the intermediate terminal 47 is negative, I choose to term the device, as a whole, a "negative" rectifier.

As contrasted with the negative rectifier of Fig. 5, I have shown in Fig. 6 a "positive" electrolytic rectifier for producing somewhat similar results. This consists of a source of alternating current 48 connected directly to load terminals 49 and 50, and two electrolytic cells connected in series and having their respective inert electrodes 51 and 52 connected to terminals 49 and 50, and their respective aluminum electrodes 53 and 54 connected to the intermediate load terminal 55. I prefer to make electrode 54 of much greater electrostatic capacity than 53, and I rely on this difference in capacity to effect the desired results. With the arrangement as described, the intermediate terminal 55 is positive with respect to terminals 49 and 50, and the electro-motive force between 55 and 50 is substantially constant and equal to the maximum value of the alternating current source, while the voltage between 55 and 49 is pulsating and reaches a maximum value approximately twice the maximum of the source.

In all of the modifications above described, the maximum steady voltage of the rectified current has been substantially equal to the maximum alternating current pressure, but in the systems I am now about to describe, the pressure available is two and even three times the maximum value of the alternating current source. This effect is produced by combining what I have termed "positive" rectifiers with "negative" rectifiers in such a way that their effects are cumulative. The principle involved is broadly applicable to any asymmetric circuit in combination with one or more electrostatic condensers.

By combining the negative rectifier of Fig. 1, with the positive rectifier of Fig. 3, I obtain the system shown in Fig. 7. One rectifier 56, has its cathode connected to the main of the source, and its anode connected through a condenser 57 to the opposite transformer main. The other vapor tube 58 has its anode connected directly to the transformer secondary and its cathode connected through the condenser 59 to the opposite terminal of the source. The junction between vapor tube 56 and condenser 57 is always at negative potential, while the junction between rectifier 58 and condenser 59 is always at positive potential, and the load 60 connected between these junctions is traversed by a unidirectional current of substantially constant potential, this potential being approximately twice the maximum value of the alternating current source. My invention will

be readily understood if it is noted that the condensers 57 and 59 are charged in parallel and discharged in series.

Fig. 8 shows a system in which three vapor tubes are utilized as asymmetric conductors. Two of the tubes, 61 and 62, have their anodes connected to a common terminal 63, and their cathodes connected respectively to the alternating current mains 64 and 65. Tube 61 is shunted by condenser 66 of relatively large electrostatic capacity. These elements constitute a negative rectifier and serve to keep the terminal 63 at a constant negative potential with respect to the alternating current main 64. Combined with this negative rectifier is a positive rectifier consisting of a vapor tube 68, having its main anodes 69 and 70, connected respectively to the line conductors 64 and 65, and its cathode connected to a load terminal 71. Condenser 73 is connected between load terminal 71 and the alternating current main 65. This positive rectifier serves to keep the load terminal 71 at a positive and constant potential with respect to the alternating current main 65. If the load 74 is connected between the charged terminals 63 and 71 current will flow from the terminal 71 to 63, and the voltage of the energy transmitted will be the resultant of the two condensers discharging in series combined with the energy delivered directly from the alternating current source by way of the vapor tubes. In other words, the unidirectional current delivered is the resultant of an alternating current having substantially the potential of the alternating current source, and a direct current having substantially double the maximum voltage of the alternating current source. The average value of the resultant is twice the maximum value of the alternating pressure wave. The effective value is the vector sum of this average value and the value of the alternating pressure wave; the maximum value is three times the maximum value of the alternating pressure wave; the minimum value is equal to the maximum of the alternating pressure wave. In these calculations the voltage drop in the asymmetric conductors and the leakage and other losses in the condensers, have of course, been excluded. It will be understood that the condensers 66 and 73 must be properly proportioned with respect to the load in order that the condenser voltage may not drop off abnormally when the load circuit is closed.

For a better understanding of the potential difference between the various parts of the system, reference may be had to Fig. 17. For convenience of reference, the terminal 63 is taken as the point of zero potential and all other parts of the system are referred thereto. The propriety of this assumption will be apparent when it is considered that terminal 63 might be grounded

and thus placed at zero potential with respect to the earth.

In Fig. 17, the potential of the terminal 63 is represented by the horizontal line 63'. The potential of the supply conductor 64 is represented by a second horizontal line 64' spaced above line 63' by a distance corresponding to the maximum voltage of the alternating supply source. This constant voltage difference is of course maintained by the storing and restoring action of condenser 66. The supply lead 65 varies in potential with respect to conductor 64 in a sinusoidal relation, as illustrated by the curve 65'. Conductor 65 is separated from binding post 71 by a condenser of large capacity and therefore binding post 71 is at constant potential from conductor 65, as illustrated by curve 71'.

From an inspection of Fig. 17 it will be seen that the maximum difference of potential between binding post 63 and binding post 71 corresponds to the maximum distance between curve 71' and curve 63' and is equal to three times the maximum impressed voltage of the system. The minimum difference of potential between these binding posts equals one times the maximum of the system. The load potential is composed of three components; two uniform and equal potentials, and the alternating current source itself, all acting in series. To express it differently, the pressure between the terminals 71 and 63 is composed of two equal uni-directional pressures with an alternating pressure superimposed upon them.

As previously stated, the potential difference between terminals 71 and 63 attains a maximum three times the maximum of the alternating current transformer voltage, and then drops to a value equal to only one times the maximum potential value of the transformer. In order therefore to obtain a uniform or practically uniform difference of potential equal to three times the maximum value of the transformer voltage, it is only necessary to store energy during the peak of the pulsating energy.

Fig. 9 shows an electrolytic system in many respects analogous to the vapor tube system of Fig. 8. Two electrolytic asymmetric conductors 75 and 76 have their inert or iron electrodes 77 and 78 connected respectively to the alternating current mains 79 and 80. Cell 75 is provided with an aluminum electrode 81 of negligible electrostatic capacity, and this is connected directly to the load terminal 82 and also to the aluminum electrode 83 of the other electrolytic cell. This last named electrode has a large surface area and is intended to have a very appreciable electrostatic capacity. The apparatus just described constitutes a positive rectifier, and maintains, or tends to maintain the load terminal 82 at positive

potential with respect to the alternating current main 80. The negative rectifier of the system consists of a single cell 84 provided with a large aluminum electrode 85 and a smaller aluminum electrode 86, this combination serving to keep the load terminal 87 at a constant and negative potential with respect to the alternating current main 79. When the alternating current main 79 is positive, current flows through cell 75 from anode 77 to aluminum electrode 81 and thus brings the load terminal 82 to positive potential and charges condenser 76. Simultaneously a positive charge is transmitted to the large aluminum plate 85 of cell 84, and this renders the electrolyte and load terminal 87 negative by driving current through the small aluminum plate 86 to the other load terminal. This negative charge cannot escape when the potential of the main 79 drops back to zero, and consequently, acts in conjunction with the positive charge on the opposite terminal to force current through any load connected between these terminals. The voltage of the current discharge is the resultant of the combined action of the condensers and the alternating current source.

When the polarity reverses and the conductor 79 becomes negative, current can flow from conductor 80 through cell 76 to electrode 83 and then through the load which connects 82 and 87, and on through cell 84 to electrode 85. The voltage of the transformer, when thus applied to the load through the two electrolytic cells, is boosted by the condenser charge held at electrode 83, and by the condenser charge at electrode 85, and it is this boosting of the transformer voltage which gives to the load circuit between 82 and 87 a maximum voltage substantially three times that of the maximum instantaneous voltage of the transformer. While conductor 80 is positive, current cannot leave electrode 86 because it is of aluminum, and, likewise, current cannot leave electrode 81, these electrodes being cut off by their insulating films as soon as the polarity of the transformer reverses.

Fig. 10 shows a combination of cells similar to that of Fig. 9, but with the addition of a cell 88 placed between load terminals 89 and 90. This cell has two opposed aluminum plates 91 and 92, the latter being larger in size and having a greater electrostatic capacity. This large electrode is connected to the positive rectifier and serves to store up energy and smooth out the pulsations of the unidirectional current delivered to the load terminals 89 and 90, so that this pressure is uniform and higher in value than the average value of the pulsating current supplied the two terminals 89 and 90. This result is effected by the condenser properties of the cell which insure its discharge at a

pressure equal to the maximum voltage of the pressure momentarily impressed on its terminals by the unidirectional pulsating pressure supplied to electrodes 92 and 91. There is, then, a uniform static charge bound up in this cell 88 having a pressure which is theoretically equal to three times the maximum value of the alternating pressure on the circuit. Any receiving device, such as a consumption circuit 93 placed across this cell 88, will be actuated by this triple voltage, and of course, will at the same time tend to lessen the uniformity in proportion to the amount of energy drawn off. That there may be an available load potential equal to three times the impressed voltage will be readily understood, when we consider that the two condensers charge in parallel with the source and then discharge in series with each other and in series with the source. This gives a maximum voltage three times the maximum impressed voltage. The charge may be continuously held at substantially this maximum value by the condenser which shunts the load.

Fig. 11 shows a system equipped with an asymmetric conductor which, so far as I am aware, possesses novel features and qualities.

30 The asymmetric conductor consists of a refractory stick 94 consisting of oxides of the rare metals or of other metals of that general nature heretofore employed in the so-called "Nernst glowers." Such materials are substantially non-conducting at ordinary temperatures and may easily be rendered conductive by heating with a flame or in any other well known manner, and will thereafter transmit current and attain a bright 40 incandescence. The glower is illustrated as provided with the usual form of resistance ballast 95.

I have discovered the important fact that such glowers not only emit light but also 45 emit energy of such a nature that it renders the adjacent space conductive for current. This conductive region extends outward for a distance of only a few milli-meters from the incandescent glower. In fact, it is confined principally or wholly to the end of the glower which is negative at the particular instant. Thus, if the glower is operated on alternating current, the conductive region shifts from one end of the glower to the 55 other at each half-cycle.

In the drawing I have illustrated conductive plates or points 96 and 97 held near the respective ends of the glower in such a position as to readily transmit current across 60 the gaps which are made conductive by the current. As the result, the intermediate load terminal 98 is maintained at a constant negative potential with respect to the alternating current main 99. The system is analogous to the vapor tube system heretofore

described and illustrated in Fig. 4 differing therefrom only in the different character of the asymmetric conductor used.

Although I have above described my basic invention as applied to single-phase apparatus, it will, of course, be obvious to a person skilled in the art that it is also applicable to poly-phase systems, and that many modifications and species will readily suggest themselves. Although I have not 75 deemed it expedient to describe such poly-phase systems at length, I have illustrated in Fig. 12 one arrangement which possesses certain novel characteristics. The electrolytic cell 100 is provided with three aluminum electrodes, 101, 102 and 103 which have a large electrostatic capacity, and which are connected to one terminal of a three phase source 104. The neutral of the source is connected through a suitable consumption 80 circuit 105 with an iron or carbon electrode 106, immersed in the electrolyte. The aluminum electrodes cannot transmit current to the electrolyte because of the protective action of the insulating films formed thereon by the electrolyte, but they do have power to take up an electrostatic charge, and to render the electrolyte at an appreciable negative potential with respect to the neutral of the three-phase source. As the result, current will flow from the neutral of the source through the load to the electrolyte and then back to the source by way of the particular aluminum electrode or electrodes which happen at the instant to be of the 90 proper polarity to receive the current.

In a single-phase electrolyte condenser, the negative charge may be considered as sent back and forth from one electrode to the other, but in a poly-phase condenser as 95 above described the negative electrostatic charge in the electrolyte shifts from one electrode to the other with a speed corresponding to the frequency of the source, and thus rotates in synchronism therewith. I 110 contemplate the use of this rotating electrostatic charge for various electrotechnical applications, and I have hereinafter indicated some of the mathematical relations thereof.

The sum of the coulomb charges on the 115 three plates is constant, and is equal to the maximum charge capable of being held by the cell with a given impressed pressure. This maximum charge does not collect at a time when the pressure across two of the 120 plates is a maximum, as in case of a single-phase condenser, but it collects when two of the three plates are at an equal positive potential with respect to the third plate.

The constant coulomb charge is equal to 125

$$(2C)\sqrt{3}/2E$$

where C is equal to the electrostatic capacity of one of the three smaller plates, and E is the "delta" alternating current pressure im- 130

pressed on the cell. The unidirectional and constant pressure set up between the electrolyte and the neutral point of the three-phase circuit is theoretically equal to the 5 maximum value of the "star" voltage of the circuit.

If one of the three electrodes be disconnected from the circuit the constant unidirectional pressure drops to

$$10 \quad \frac{1}{\sqrt{2}} E,$$

or .707 times the impressed "delta" pressure. The total energy stored in the 15 condenser is constant at all times, and is equal to

$$15 \quad \frac{\sqrt{3}}{2} C E^2$$

20 where C is the capacity of one of the plates and E is the "delta" pressure impressed on the cell.

What I claim as new and desire to secure by Letters Patent of the United States, is,—

25 1. The combination with a source of alternating current, of a condenser connected to receive energy therefrom, stationary means for preventing deliverance of energy to said condenser during alternate half waves of 30 said source, a load circuit and connections between said source, said condenser and said circuit, whereby a potential difference greater than that of said source is applied to the circuit.

35 2. The combination with a source of alternating current, of a condenser receiving energy therefrom, an asymmetric conductor connected in series with said condenser, and a unidirectional load circuit connected across 40 said asymmetric conductor.

45 3. The combination with a source of alternating current, of a condenser, stationary means for delivering energy to said condenser during each alternate half wave of said source and for preventing the deliverance of energy thereto during the remaining half wave, and a load circuit receiving energy by way of said condenser at a maximum potential higher than the maximum 50 potential of said source.

55 4. The combination with a source of alternating current, of means for accumulating an appreciable electrostatic charge, a load circuit, and stationary means of negligible reactance for conducting said charge to said load as unidirectional current.

5. The combination with alternating current mains, of an asymmetric conductor and

means for storing an electrostatic charge connected across said mains and tending to 60 maintain a constant difference of potential across said storing means, and translating devices connected to receive energy from said storing means by way of said alternating current mains. 65

6. The combination with alternating current mains, of a condenser connected to take energy therefrom, means for limiting the delivery of energy to said condenser, said means having greater conductivity in one 70 direction than in the other, and a translating device connected in circuit with said condenser and subjected to a maximum difference of potential, substantially higher than the maximum instantaneous potential across 75 said mains.

7. The combination with alternating current mains, of a conductive path therebetween including a condenser, and a second path common to a part of said conductive 80 path and including translating devices, the places of connection for said translating devices being at parts of said conductive path having a maximum potential higher than the maximum potential across said alternating 85 current mains.

8. The combination of an alternating current source, an asymmetric conductor connected to said source, a condenser in circuit therewith, and a load circuit receiving energy by way of said condenser at a potential higher than the maximum potential of said 90 alternating current source.

9. The combination with alternating current mains, of an asymmetric conductor, and 95 means for storing an electrostatic charge at substantially the potential of said source, said conductor and storing means being connected across said mains, and a load circuit connected across said asymmetric conductor. 100

10. The combination of a source of alternating current, condensers for storing electric energy from said source in a plurality of places, asymmetric means for preventing the return of said energy to said source, and 105 a load circuit connected to receive the stored energy from one of said condensers as a unidirectional flow boosted in voltage by energy from another of said condensers.

In witness whereof, I have hereunto set 110 my hand this 13th day of October, 1906.

CLARENCE IRVING ZIMMERMAN.

Witnesses:

JESSIE B. MCVEAN,
MICHAEL J. NOONAN.

It is hereby certified that in Letters Patent No. 1,099,960, granted June 16, 1914, upon the application of Clarence Irving Zimmerman, of Niagara Falls, New York, for an improvement in "Electric Converters," errors appear in the printed specification requiring correction as follows: Page 3, line 24, before the word "substantially" insert the word *of*; page 7, line 14, for the word "simusoidal" read *sinusoidal*; same page, line 28, after the word "maximum" insert the words *impressed voltage*; and that the said Letters Patent should be read with these corrections therein that the same may conform to the record of the case in the Patent Office.

Signed and sealed this 7th day of July, A. D., 1914.

[SEAL.]

R. F. WHITEHEAD,

Acting Commissioner of Patents.
